US00D929512S

(12) **United States Design Patent** (10) Patent No.: **US D929,512 S**
(45) Date of Patent: **** Aug. 31, 2021**

(54) **WALL MOUNT FOR PULL UP BAR**(71) Applicant: **Coulter Ventures LLC**, Columbus, OH (US)(72) Inventor: **Nash Dunahay**, Gahanna, OH (US)(73) Assignee: **Coulter Ventures, LLC.**, Columbus, OH (US)(**) Term: **15 Years**(21) Appl. No.: **29/650,226**(22) Filed: **Jun. 5, 2018**(51) LOC (13) Cl. **21-02**

(52) U.S. Cl.

CLAIM

The ornamental design for a wall mount for pull up bar, as shown and described.

DESCRIPTION

FIG. 1 is a top, front, left perspective view of a wall mount for pull up bar showing my new design;
FIG. 2 is a top, front, right perspective view thereof;
FIG. 3 is a front view thereof;
FIG. 4 is a left side view thereof;
FIG. 5 is a right side view thereof;
FIG. 6 is a top view thereof;
FIG. 7 is a bottom view thereof; and,
FIG. 8 is a top, front, left perspective view of the design in FIGS. 1-7 positioned above a doorframe shown as example environment.

The broken lines immediately adjacent to the shaded area define the bounds of the claimed design and form no part thereof. The broken lines depicting the remainder of the wall mount for pull up bar show features that form no part of the claimed design. The broken lines depicting a doorframe shown as example environment in FIG. 8 show features that form no part of the claimed design.
